NONARCING INTERRUPTING SWITCH

William C. Gregory, Compton, Calif.

Application January 4, 1949, Serial No. 69,205

4 Claims. (Cl. 200—150)

1

This application is a continuing of my original application filed January 6, 1944, Serial No. 517,275, and now abandoned.

Briefly stated this invention relates to the following arts:

1. The breaking of an electric circuit;
2. The making and breaking of an electric current;
3. The making and/or breaking at least one electric circuit at predetermined intervals, without causing an appreciable arc.

The following refers to the drawings:

Figure 1 shows a spring energy accumulating, fluid activating, and arc-quenching switch. The said activating fluid operating said switch is controlled by means of a rotating valve.

Figure 2 shows a compressed air accumulating, fluid activated, and arc-quenching switch. The said activating fluid operating said switch is controlled by means of a rotating valve.

Figure 3 is a side elevational view of Figure 1 and/or 2, slightly modified. In this embodiment a latch is provided so as to hold open a switch, when it is desired.

Figures 4 and 5 show diagrammatically the method of controlling a plurality of fluid activated and arc-quenching switches. The said activating fluid operating said switches is controlled by means of a rotating valve.

Figure 6 shows a slightly modified end view of Figure 4 and/or 5.

Figures 7, 8, and 9 show schematically how the fluid activating arc-quenching switch could be used to convert alternating current to direct current when the rotating valve means is driven in synchronism with the said alternating current.

Figure 9 shows schematically how the fluid activating arc-quenching switch could be used to invert direct current to alternating current when the rotating valve means is driven at a predetermined speed.

Figure 10 shows an end view of an electrode having a plurality of ducts. The said ducts carrying the activating and/or arc-quenching fluid.

Figure 11 shows the end elevation of a reciprocating or vibrating fluid activated and arc-quenching switch, while Figure 12 shows the side elevation. The said activating fluid switch is controlled by means of a rotating valve.

Figure 13 shows an activating and arc-quenching fluid entering the switch between a rotating valve means and an electrode. To have an activating fluid travel as short a path as possible after passing the rotating valve means is desirable.

2

Figure 14 shows the end view, while Figure 15 shows the side elevation of a fluid activated and arc-quenching switch capable of compressing the said activating fluid. In this embodiment the compression means is an integral part of the rotating valve means.

Figure 16 shows the end view, while Figure 17 shows the side elevation of a rotating power-driven switch. The rotating portion of said switch acts as a rotating valve means, opening and closing the ports through which the arc-quenching fluid flows.

Figure 18 shows the side elevation, while Figure 19 shows the end elevation of a fluid activated and arc-quenching rotating valve means and switch.

Figure 20 shows the end view, while Figure 21 shows the side elevational view of a cylindrical type fluid and arc-quenching switch and valve means.

A more specific explanation follows.

Figure 1 shows a spring compression energy accumulating switch. In this embodiment the circuit that is to be controlled is connected to the switch at 1 and 2. The actuating and arc-quenching fluid 3 enters at the base of the stationary electrode 5. The flow of the said fluid is controlled by the action of the rotating valve means 4. As the said fluid passes through the port in the stationary electrode 5, the fluid forces the movable electrode 6 from its seat, thus breaking the circuit. The escaping fluid 7 blows out any arcing that may be present. As the movable electrode 6 moves away from the stationary electrode, energy is accumulated in the spring 8. A better contact is obtained between the support for the movable electrode and the movable electrode by a spring tension bar 9.

In this embodiment the valve means 4 may be driven by mechanical force, or manually operated by aid of the handle 10.

Figure 2 shows an air compression energy accumulating switch. This embodiment is similar to Figure 1. The circuit to be controlled is connected at 11 and 12. Low resistance metal to metal is accomplished by having the movable electrode pass through the bath of conducting fluid, for example mercury, 13. This bath is made fluid tight with a packing 14. The quick re-seating of the electrode is assured by the air compressed in chamber 16. A plurality of switches may be controlled by one driving unit 17 as indicated in Figures 1 and 2. For example, when an alternating current is to be rectified by 55 at least one switch, the shaft 4 carrying the

valves is made to rotate at a predetermined speed so as to synchronize with the sine wave of the alternating current. In this case a synchronous motor 17 (or synchronously operated magnets) may be used for the driving force. Synchronization between the synchronous motor and the alternating current that is to be rectified is obtained by revolving the said motor concentrically to the axis of the armature, on the slide 18. When synchronization has been established the motor is clamped into place by the clamp 19.

Electrical synchronization between a switch and synchronous motor may be established by passing all of the current to be rectified through the synchronous motor or connecting the synchronous motor in parallel with the rectifying switches.

Figure 3 shows a slightly modified view, at right angles to Figures 1 and 2. In this embodiment an insulating shroud 20 is placed around the stationary electrode 21. The object of this shroud is to save on the consumption of fluid that is necessary for actuating the movable electrode. The current to be controlled is connected to the stationary electrode 22, and the movable electrode by a flexible "pig-tail" 23. When the switch is used intermittently, the movable electrode may be held away from the stationary electrode by a latch 24.

Figure 4 shows a switching unit, the stationary electrode 25, and the movable electrode 26 both having flat faces. Figure 5 shows a switching unit, the movable electrode taking the form of an inverted cone 27. This cone-shaped electrode engages the stationary electrode 28 as illustrated. The movable electrodes of Figures 4 and 5 are actuated by a common rotating valve means 34. This rotating valve is insulated as at 33 so as to maintain electrically separated switching units.

The circuit may be connected as indicated at 29, 30, 31, and 31'. In this embodiment a portion of the switching unit is connected directly to the load. The illustration shows said portion immersed in the electrolyte 35. The electrolyte is shown residing in the receptacle 32. This electrolyte 35 is the load or resistance of the newly transformed energy. The electrolyte may be a conducting fluid, a molten alloy, a molten salt, a saline solution and/or the like.

Figure 6 is an end view of Figure 4 and/or 5. This figure shows the rotating valve shaft 34 having a plurality of openings. These openings register with the duct in the stationary electrode. When registration takes place, the fluid passes through the opening that is in register, thence through the duct in the stationary electrode and escapes from the duct by raising the movable electrode. This movement of the movable electrode opens the circuit. The escaping fluid prevents the damaging arcing effect on the electrode.

Figure 7 shows schematically one side of a three phase Y connected transformer. This transformer is connected to a polyphase switch as herein described. The three phase switch consists of three switches and a collecting ring. The collecting ring 38 may be similar in construction to the slip rings found on alternating generators. The three switches and the collecting ring are actuated by a common means. The load 36 is connected between the collecting ring 38 and the center tap 37 of the transformer.

Figure 8 shows schematically one side of a three wire single phase transformer. The load 40 is connected into the outer wires of the said transformer by two switches 39 and 39' and the center wire of the said transformer. The switches thus

connected and driven in synchronism with the electric energy supplied to the said transformer produces a unidirectional current through the load 40.

In rectifying an alternating current the switches must open and close in synchronism with the current and voltage. It is desirable to have approximately a 100 percent power factor when rectifying an alternating current. The switches should open and close as the current and voltage pass over the zero value. The switches are activated and synchronized with the current to be rectified by aid of a synchronous device, for example a synchronous motor, or a series of synchronously operated lifting magnets, as shown diagrammatically in Figures 7, 8 and 9.

Figure 9 shows one side of a three phase Y connected transformer. In this embodiment a direct current is made into an alternating current by systematically opening and closing the switches 41, 41a, and 41b at a predetermined speed. The battery 42 is connected to the slip ring 43 and to the center of the Y connected transformer.

Figure 10 shows the end view of a stationary electrode having a plurality of fluid conducting ducts, instead of one duct as above described.

Figure 11 shows the end elevation of a vibrating electrode switch. This switch can be operated in synchronism with an alternating current so as to rectify the current into direct and/or pulsating current or change the frequency of the prime alternating current. The new frequency, after passing a switch, may be greater or less than the prime frequency.

In this embodiment the activating and arc-quenching fluid is discharged from the orifices located at approximately 180 degrees from each other. The current is connected to the vibrating electrode and the structures containing the orifices.

The vibrating electrode 45 is made to make and break contact with the stationary electrodes 46 and 47 by the alternating impacts of the activating and arc-quenching fluid. The direction of flow of the said fluid is controlled by the rotating distributing valve 48. The said fluid may be energized by the pump 49. This pump may be driven from the same shaft that drives the rotating distributing valve 48. The said shaft is driven at a predetermined speed by connecting the said shaft to a suitable driver, such as a motor, steam turbine, or is belt driven.

Figure 12 is a side elevation of Figure 11 taken through the duct through which flows the fluid and also the center of the vibrating electrode A—A.

Figure 13 shows a modified embodiment of the rotating distributor valve 48. It is desirable to have the activating and arc-quenching fluid travel the shortest possible route after passing the rotating valve means 53. In this valve the fluid enters at 52 and is sent to the predetermined electrode by the said valve 53. The electrodes 46 and 47 are separated electrically from each other by the insulators 55. The circuit is completed through the connections 54—54a and 54—54b.

Figure 14 is an end elevation of a rotating valve means. In this embodiment the rotating valve means plays a dual part, namely, as a centrifugal pump and as a distributor valve. The pumping action of the valve picks up the activating and arc-quenching fluid and then places the fluid under pressures due to the centrifugal and centripetal forces. The fluid under pressure from the

pumping action is forced through the rotating valve, thence through the orifices of the electrodes. In this embodiment a vibrating electrode is caused to vibrate in a manner similar to Figures 11 and 12.

The rotor 56 of the centrifugal pump 57 engages the incoming fluid. The centrifugal and centripetal forces force the fluid (the fluid now under pressure) through the rotating distributor valves to the nozzles of the electrodes 59 and 60. The vibrating electrode 58 is made to vibrate between the electrodes 59 and 60 by the driving force imparted by the escaping activating and arc-quenching fluids. The arrows indicate the direction of flow of the fluid. The electrodes 59 and 60 are insulated as at 61.

In this embodiment the rotating distributor valve and centrifugal pump may be driven in synchronism with an alternating current that is to be changed and/or altered or the said valve may be driven non-synchronously.

Figure 15 is a side elevation of Figure 14 taken to show the fluid flow by the dotted line D—D. The rotating distributor valve and centrifugal pump combination 56 and the hollow tail shaft 63 are connected to a suitable driving means through the solid shaft 64.

The suction side of the said combination is stabilized by mounting the hollow shaft in a box and/or gland 65. The electrodes 59 and 60 are separated by the insulators 61. The switch is connected to the outer circuit through the stationary electrodes 59 and 60 by the lead 68 and the vibrating electrode 58. The vibrating electrode 58 is connected to the outer circuit through the flexible connections 68.

Figure 16 shows the end view of a mechanically driven rotating arc-quenching fluid switch. The switch here shown is composed of four segments 70, 71, 72, and 73. The said segments are electrically separated but mechanically one unit. The said segments are connected to a common terminal 74 by the revolving contactor or switch 75. In this embodiment the operating fluid is released from the leaving edges of the segments and/or from the trailing edges of the said revolving switch.

The said fluid is forced from the hollow shaft 76 to the trailing edge of the switch 75 through the duct 79. The said fluid is also forced from the bustle pipe 78 through the duct 79 to the parting edge of a segment, for example 73, the orifice of the delivery duct being located at 80.

The bustle pipe 78 is made either of a non-conducting material or of a conducting material, in which case the various sections of the pipe are properly insulated from each other section.

Figure 17 is a side elevational view taken through Figure 16 at E—E. In this embodiment a switch is shown capable of rectifying a single phase alternating current to a unidirectional current. The transformer furnishing the said current is here illustrated as a three-wire secondary and is shown schematically in Figure 9.

The segments 70 and 72 are connected together as at 81, Figure 17, and segments 71 and 73 are connected as at 82. These two terminals 81 and 82 are connected to the outside wires of the said three-wire secondary. The center wire of the said transformer is connected at 74.

The revolving switch or contactor 75 is driven at a predetermined speed by connecting the driving unit to the shaft as at 85. When an alternating current is to be rectified, the revolving switch is driven by a synchronous motor in such

a manner that the switch is kept in synchronism with the zero value of the current and/or voltage.

The shaft may be stabilized by the bearing and/or gland 86. The arrows 84 indicated the flow of the said fluid. The arrow marked F shows the direction of the rotating switch.

The switch in this embodiment may be driven by the escaping arc-quenching fluid, provided the said fluid is under sufficient pressures. When the switch is thus activated, a speed control device must be supplied. A speed control device may be attached to the shaft as at 85 instead of at the synchronous drive as above described.

Figure 18 is the side elevational view while Figure 19 is an end elevational view of a fluid-activated and arc-quenching rotating valve means and switch taken through G, H, and J.

The stationary portion of this embodiment consists of at least two stationary rings 87 and the collector ring 88. The said rings are electrically separated but held together mechanically in one unit. The said rings 87 are made up of a plurality of segments. The said segments 94, 95, 96, and 97 are also electrically separated but held together mechanically in one unit.

The said segments in the said electrically separated rings are connected periodically electrically through the revolving connector bar 89. The said bar is mounted movably on the shaft 90 by the rocker joint 102.

The activating and arc-quenching fluid that is delivered to the said connector bar 89 is forced through the hollow shaft 90, through the duct 106, through the flexible duct 108 and thence through the duct 91 and finally discharged at the nozzle 107.

The activating and arc-quenching fluid that is delivered to the said stationary segments is forced through the bustle pipe 93 into the duct 92 and thence through the nozzle 109.

The non-conducting portion of the rotating switch may be air or material in the vapor phase as at 103, or the non-conducting portion of the rotating switch may be made of a non-conducting or difficult conducting solid as indicated at 104. The radial face on the said non-conducting solid may be smooth, or the face may be serrated as indicated at 105.

The non-conducting portion of the stationary 50 portion of the switch may be air or material in the fluid phase as at 98, 99, 100, and 101, or the non-conducting or difficult conducting portion of the stationary rings of said switch may be made of a non-conducting and/or difficult conducting solid. The radial face on the said non-conducting or difficult conducting portion may be smooth as at 98 and 99 or serrated as at 101, or the said stationary portion may be made up of a graduated series of non-conducting or difficult conducting materials as indicated at 101, for example the first series to have a resistance of X, the second series to have a resistance of 2X and so on.

This style of switch may be activated by mechanical means by mounting suitable mechanical means to the shaft 90 and then turning the said shaft at a predetermined speed. However, it is preferable to activate the switch by the escaping activating and arc-quenching fluid. When pressure of the activating fluid is sufficient to drive the switch at a positive accelerating speed, a speed regulator means must be attached to the shaft 90.

Electrical contact between the sliding and stationary electrodes or segments may be established by having the said activating and arc-quenching

fluid a conductor of an electric current, or the revolving electrode 89 may be made to engage in the inner surface of the stationary electrodes as indicated. When the revolving electrode 89 is mounted on a rocker 102, centrifugal force presses the free end of the electrode against the stationary electrodes, thus assuring positive contact.

A resistance metal tip may be welded to the breaking edge of the electrode as indicated at 109 or on the trailing edge of the rotating switch as at 107. The resistance of the said tip and said trailing edge may be graduated as explained above.

Figure 20 shows the end view of a fluid activated arc-quenching rotary switch, taken through either electrodes 114, 115, 116 of Figure 21. 117 is the common terminal or slip ring. Figure 21 is the front elevational view of Figure 20. In this embodiment the stationary electrode 111 is held at proper tension against the revolving electrode or connector switch by spring tension or the like in a manner similar to holding the brushes on a generator.

The length along the radical faces of the stationary and/or rotating electrodes may vary so that the electric energy may flow in a given sequence.

The small arrows 112 indicate the direction of flow of the activating and arc-quenching fluid.

The radial surface of the non-conducting sections 113 of the revolving portion of the said switch may be smooth or serrated as illustrated. A serrated face is preferred.

In rectifying a three phase current the common electrode 117 engages the revolving continuous conductor 118. The electrodes 114, 115 and 116 carry the alternating current and engage segments of the revolving conductor as at 0—60—120 degrees apart. The said segments are connected to the said continuous conductor as indicated at 120 and 123.

This style of switch may be used to rectify an alternating three-phase circuit as indicated schematically in Figure 7, or direct current may be made into a three-phase or a poly-phase circuit at will. Furthermore, a variable-frequency poly-phase circuit can be maintained at will.

A large number of the above named switches could be attached to one shaft, and a sequence of operations could be preformed automatically to produce a given process.

Variable resistances 124 and variable conductances 125 are illustrated at the parting edges and the trailing edges in Figures 19 and 20.

K—K is taken through the fluid flow duct as indicated at terminal 114. The contact bars 123 on the revolving shaft are 60 degrees apart from each other.

The examples given are for illustrating a few of the uses of this style of switch and does not limit the said switch to the examples given.

This invention has the following values in industrial electricity:

1. As a circuit breaker where large sources of electric energy are being handled.
2. As a regulating switch, for example, in spot and/or resistance welding.
3. As a process switch for opening and/or closing a plurality of switches in a predetermined sequence.
4. As a converter and/or rectifier of alternating current to direct and/or pulsating current.
5. As an inverter of a unidirectional current to an alternating current.
6. As a chopper of an electric current.

7. As a frequency changer,
8. As a variable frequency changer for driving alternating current machinery at various speeds,
9. As a high frequency machine for furnishing high frequency for metallurgical processes and heat treating processes,

10. As a circuit interrupter.

The said switch is activated in the following manners:

1. By an activating fluid,
2. By mechanical means,
3. By electrical means.

The activating and/or arc-quenching fluid, performs the following services:

1. Quenches the arc,
2. Quenches the arc and/or activates the switch.

The activating and/or arc-quenching fluid is controlled by means of a rotating valve.

The activating and/or arc-quenching fluid may be in the vapor and/or liquid phase.

The said fluid when in the vapor phase may be composed of the following:

1. An inert gas such as argon, helium, hydrogen, nitrogen and others,
2. By a hydrocarbon or a substituted hydrocarbon,
3. Steam and the like.

The said fluid when in the liquid phase may be composed of the following:

1. A hydrocarbon and/or substituted hydrocarbon and the like,
2. Non-conducting solutions,
3. A conducting solution.

The said fluid in either phase may contain a lubricant such as colloidal graphite and the like.

The pressures required to operate the said switch may vary from a few ounces to several hundred pounds or more per square inch depending upon the weight and size of the switch, the magnitude of the electric load, the speed of opening and/or closing the circuit, and other operating conditions.

The said switch may be operated by the following methods:

1. Manually,
  - (a) Close to the switch,
  - (b) Remote control;
2. Mechanically,
  - (a) Reciprocating action,
  - (b) Oscillating action,
  - (c) Rotating action.

The rotating valve means which controls the arc-quenching fluid is actuated by the following:

1. Mechanical means, e. g.,
  - (a) Non-synchronous motors,
  - (b) Synchronous mechanisms,
  - (c) Controllable speed mechanisms;
2. Fluid drive, for example,
  - (a) Turbine effect:
    - (a') To drive a switch,
    - (b') To drive a switch and quench an arc;
  - (b) Pulsating effect of the escaping quenching fluid and maintained at a predetermined speed.

The speed and/or number of makes and breaks per unit of time depends upon whether the said switch acts in the following ways:

1. A converter, in which case the switch opens and closes as the current, and voltage (100% power factor) passes over the zero point. In this case, makes and breaks must be accomplished by a synchronous machine, such as a synchronous motor, synchronous operated magnets and the like.

2. An inverter, in which case the switch makes and breaks at predetermined regular intervals and may vary from less than one to 50,000 or more cycles per second. In this case a direct current may be changed into an alternating current.

3. A chopper, in which case the switch may make and break at irregular and/or regular intervals without any reference to the zero value of the current and/or voltage.

The said switch may be provided with variable resistances and/or variable conductances located between the conductor and non-conductor portions of the said switch.

These variable resistances and variable conductors may be composed, for example of the following substances:

(a) Of metal oxides such as copper oxide, iron oxide (magnetite) and the like.

(b) Of elements such as tellurium, selenium, graphite, silicon, germanium, and the like.

(c) Of salts such as iron silicides, iron silicates (ferro-silicon) and the like.

(d) Of alloys Nichrome, and the like.

(e) Of mixtures such as graphite dispersed in clay and the mixture then baked similar to material found in graphite crucible, brushes and the like, and mixtures produced from molten mixtures or melts such as iron-saturated with an excess of carbon, iron saturated with a non-metal such as iron saturated with silicon or silica and the like.

(f) Glass heavily loaded with a conducting metal such as ferro-silicon and the like.

The said variable resistances and variable conductances may have a range from the conductivity of the conductor in the switch to the resistivity of the non-conductor in the switch.

The said variable resistance and variable conductance may be made a part of the circuit by:

(a) Inserting the said resistance (possibly a number of pieces each piece having a different resistivity or conductivity, mechanically within said switch.

(b) Welding various pieces of material together and then machining the structure in such a manner that as the switch operates the conductivity increases to a maximum and then to a minimum.

(c) Flowing by fusion various materials together and then machining the structure in such a manner that as the switch operates the resistivity of the flow of electric current decreases to a minimum and then to a maximum.

I claim to have invented the following:

1. In a device of the class described a stationary member and a moving member, said members having a variable conductivity said variable conductivity obtained by using a plurality of materials having different conductivity, said materials united into a unit mass, said moving member

adapted to make and break repeatedly at a predetermined speed an electric current, said moving member motivated at least in part by a fluid under pressure, the exhaust of said fluid quenching an arc of said current.

5 2. In a device of the class described a moving pendulum-mounted reciprocating member adapted to make and break at a predetermined uniform speed an electric current, said member motivated by a fluid under pressure, said fluid being metered out by a revolving constant-speed measuring device, the exhaust of said fluid quenching an arc of said current.

3. In a device of the class described a stationary member and a moving member, said moving member having a variable conductance, said variable conductance obtained by using at least two materials having different conductivity, said materials united into a unit mass, said moving member adapted to make and break repeatedly at a predetermined uniform speed an electric current, said moving member motivated by a fluid under pressure, the exhaust of said fluid quenching an arc of said current.

15 25 4. In a device of the class described a stationary member and a moving member, said members having a variable conductance, said conductance separated by a variable resistance, said variable conductance obtained by using at least two materials having different conductivities, said conductive materials united into a unit mass, said variable resistance obtained by using at least two materials having different resistivities, said resistive materials united into a unit mass, said moving member adapted to make and break repeatedly at a predetermined uniform speed an electric current, said moving member motivated by a fluid under pressure, the exhaust of said fluid quenching an arc of said current.
